(**) Term: **15 Years**

(21) Appl. No.: **35/505,063**

(57)

CLAIM

(22) Filed: **Dec. 8, 2017**

The ornamental design for a sterilization kit for water purifier, as shown and described.

(80) **Hague Agreement Data**

DESCRIPTION

Int. Filing Date: **Dec. 8, 2017**

1. Sterilization kit for water purifier

Int. Reg. No.: **DM/099562**

1.1 : Perspective

Int. Reg. Date: **Dec. 8, 2017**

1.2 : Front

Int. Reg. Pub. Date: **Jun. 8, 2018**

1.3 : Back

(30) **Foreign Application Priority Data**

1.4 : Left

Jun. 8, 2017 (KR) 30-2017-0026081

1.5 : Right

(51) LOC (11) Cl. **23-01**

1.6 : Top

(52) U.S. Cl.

1.7 : Bottom

USPC **D23/207**

1.8 : Perspective view 2

(58) **Field of Classification Search**

The broken lines depict portions of the sterilization kit for water purifier that form no part of the claimed design; reproduction 1.1 is a front perspective view of the sterilization kit for water purifier; reproduction 1.2 is a front view thereof; reproduction 1.3 is a back view thereof; reproduction 1.4 is a left view thereof; reproduction 1.5 is a right view
